UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,120,746.

Specification of Letters Patent. Patented Dec. 15, 1914.

Application filed March 17, 1913. Serial No. 754,789.

To all whom it may concern:

Be it known that I, FRANK C. RINSCHE, a citizen of the United States, residing at Detroit, in the county of Wayne and State 5 of Michigan, have invented a certain new and useful Improvement in Adding-Machines, of which the following is the specification.

The object of my present invention is to 10 facilitate the performance of multiplication by the process of repeated addition.

It is a common practice with the ordinary 15 adding machine to perform multiplication by setting down amount keys representing the multiplicand, setting down the familiar repeat key, operating the machine a number of times corresponding with the first digit of the multiplier, then releasing the repeat key and the amount keys and again setting 20 down corresponding amount keys one or more orders over to correspond with the order of the next significant digit of the multiplier, again setting down the repeat key and then operating the machine a number 25 of times corresponding with such digit of the multiplier, and so on.

My present invention provides an improved equipment whereby the resetting of amount keys for higher digits of the multiplier, as well as successive manipulation of 30 repeat and release keys, is done away with. Thus an initial setting up of the multiplicand by depression of amount keys suffices for the entire process of multiplication without regard to the number of digits in the multiplier. This I accomplish without recourse to any such scheme as a supplemental superimposed keyboard laterally shiftable over the regular keyboard, and without recourse to any such scheme as pulling down higher order keys or setting their indexing devices as controlled by initial depression of lower order keys.

According to my invention the actuators for the registering wheels having first been released and operated under control of the stop devices set by the amount keys in the usual manner, an additional set of multiplier stops become effective, these stops being laterally shiftable step by step so as to serve for regulating the operation of higher order actuators when the multiplying is

by higher order digits of the multiplier. I also provide means for suspending the usual printing and line spacing while the multiplication by repeated addition is in progress, and I furthermore provide improved means for automatically regulating the number of operations of the machine according to the multiplier digits so that the user does not have to keep mental count of operations as is the case when the ordinary adding machine is employed for multiplication purposes.

With these and incidental objects in view, the invention consists in certain novel features of construction and combinations of parts, the essential elements whereof are recited in the appended claims and a preferred form of embodiment of which is described in detail hereinafter and illustrated in the accompanying drawings which form part of this specification.

Of said drawings, Figure 1 represents in left side sectional elevation a machine of the well known Burroughs type equipped with mechanism embodying my invention; Fig. 2 is a similar right side sectional elevation; Fig. 3 is a sectional elevation of a part of the machine viewed from the same side as Fig. 1 and illustrating the effect of depressing an amount key; Fig. 4 is a somewhat similar view but further sectionalized and differing also from Fig. 3, in illustrating a changed relationship of parts which comes about at the middle of a cycle of operation of the machine; Fig. 4^a is a fragmentary plan view of parts appearing in sectional elevation at the upper left hand portion of Fig. 3; Fig. 5 is a sectional rear elevation taken substantially on line 5-5 of Fig. 1 with parts at normal; Fig. 5^a is a similar view illustrating the effect of setting the multiplier stops in effective position and operating the machine with lower order keys depressed for setting up the multiplicand, the condition illustrated being that which would exist at the middle of a cycle of operation of the machine; Fig. 6 is a similar view showing the same multiplier stops in action for multiplying by the highest digit of the multiplier; Fig. 7 is a sectional elevation of a limited number of parts of the machine looking from the right; Fig. 8 is a

horizontal section taken on the line 8—8 of Fig. 7; Fig. 9 is another sectional elevation looking from the right but including different parts from those shown in Fig. 7; Fig. 10 is a similar view illustrating a changed condition due to depression of the special key illustrated in these two figures; Fig. 11 is a sectional rear elevation of parts appearing at the right of Fig. 9; Fig. 12 is a horizontal section taken substantially on the line 12—12 of Fig. 9; Fig. 13 is a right side sectional elevation similar to the upper part of Fig. 2 but on a larger scale and disclosing additional parts under the keyboard plates; Fig. 14 is a horizontal section taken substantially on the line 14—14 of Fig. 13; Fig. 15 is a view similar to Fig. 13 though further sectionalized and also differing in illustration of a changed relationship of parts due to depression of one of the multiplier keys; Fig. 16 is a fragmentary cross section taken on line 16—16 of Fig. 13 with the multiplier key at normal; Fig. 17 is a similar cross section taken on line 17—17 of Fig. 15; Fig. 17^a is a fragmentary horizontal section taken substantially on the line 17^a—17^a of Fig. 15; Fig. 18 is a top plan view of the keyboard of the machine; Figs. 19, 20, 21 are views similar to the left hand part of Fig. 9, illustrating a modification, at normal and in two stages of operation, respectively; Fig. 22 is a horizontal section on line 22—22 of Fig. 19.

Amount keys 291 are arranged as usual in several parallel rows extending from front to rear and their stems slide through upper and lower keyboard plates 213 and 212 and operate upon the familiar bell cranks 217 which set the stop wires 270 for limiting the descent of racks 610. Said bell cranks also act as usual to slide rearwardly the detent plates 214. The racks 610 are mounted in the usual way upon the front ends of levers 611 and the latter carry the customary sets of type at the rear. The registering wheels and the controlling mechanism therefore, including the totaling system, are arranged in the usual way which is now so familiar through disclosure in many prior patents and through extensive use in machines upon the market as to require no explanation to those skilled in the art. This is also true of the shifting paper carriage at the rear and the line spacing mechanism and likewise the hammer mechanism for driving the type against the platen, though in connection with the line spacing and hammer mechanisms I shall have occasion hereinafter to refer specifically to some of the familiar parts in connection with a description of means for suspending line spacing and printing during multiplication.

Referring first to the special equipment for facilitating control of the racks 610 in multiplication, this is located at the upper

rear part of the machine and comprises a set of vertically slideable stop fingers 10, of which there are as many as there are registering levers 611 in the machine (see Figs. 5 and 6). These stop fingers are mounted in a laterally shifting carriage which comprises a bed plate 12 grooved to receive the fingers, and a cover plate 12^a screwed to the bed plate and confining the stop fingers in the grooves (see Fig. 4). The carriage is mounted to slide upon cross shafts, the lower one of which, designated 207, is the familiar rock shaft of the key releasing bail. The upper shaft 17 is especially provided and has other functions than that of merely supplying a guide for the carriage. The latter is normally held to the right by a spring 12^b (Fig. 5), the position being to the left in this figure because the same is a rear elevation. In this normal position of the carriage the stop fingers 10 stand above spaces between the levers 611 and are themselves spaced apart so that said levers may rise between them when the multiplying equipment is not in use and the machine is being employed in the ordinary way for adding and listing purposes.

The stop fingers are put in position for use by moving the carriage a half-step so as to bring these fingers directly over the levers 611 respectively so that any levers which move farther than to merely set up cipher type, in an operation of the machine, will lift the stop fingers, as illustrated in Fig. 5^a.

The multiplier stop fingers 10 are limited in their downward movement by abutment of lugs 10^a at their upper ends against the horizontal edge of a cut-out portion of the plate 12^a, as shown in Fig. 5, and the stop fingers in their lowest position have their lower ends spaced from the upper edges of the lever 611, a distance equivalent to the movement of said levers from normal to positions for setting up cipher type. When the stop carriage has been moved over a half step and amount keys are operated for setting up the multiplicand and the machine is then operated and certain of the stop fingers lifted as before stated, all of the stop fingers will be locked so that those which have been lifted may serve to measure the movements of the registering levers in subsequent operations to just the same extent that said levers move when lifting the stop fingers, while the balance of the stop fingers, under the condition illustrated in Fig. 5^a, will check any upward movement of associated levers beyond positions where they set up cipher type. As the carriage is stepped over to provide for multiplying by successive digits of the multiplier, it becomes necessary to restrain levers which, in previous operations, were stopped by the set fingers. For this purpose the cover plate 12^a of the car-

riage is formed with a depending portion taking the form of a comb 12^b whose tines are adapted to move over the levers, as illustrated in Fig. 6, and prevent such levers 5 from moving at all.

It will be understood from what has been thus far described that by setting the stop carriage in position over the levers 611 and then depressing lower order keys representing the multiplicand and operating the machine, certain of the stop pins 10 will be set and locked in a position where they may constitute stops serving in the same way as the usual stop wires 270 for regulating 10 movements of the levers. Obviously, by maintaining these stop fingers so positioned, they will serve to measure movements of the levers uniformly in the successive operations of the machine the same as in the case of 15 operating the usual adding machine with its repeat key set and the stop wires therefore maintained in stopping position. It will further be seen that by moving the stop carriage over one order while still maintaining 20 the set stop fingers in position, these stop fingers will similarly serve for measuring corresponding movements of stop levers one order higher, that is to say a set of levers omitting the lowest order of those first employed and including a higher order lever. Thus it will be clear that multiplication by 25 the next higher digit of the multiplier can be performed, without setting up the multiplicand again by depression of amount keys. 30 It will further be manifest that this same procedure can be pursued to the limit of the denominational capacity of the machine. The machine here shown is what is known as a fifteen bank machine, to wit a machine 35 of fifteen numerical orders. Fig. 5^a shows a setting-up for a multiplicand of four orders of denominations. It is clear that the multiplicand of this denomination could be carried on through twelve denominations of a multiplier. Fig. 6 illustrates what would be the 40 condition when multiplying by the twelfth digit of the multiplier.

Referring next to the matter of locking and unlocking the stop fingers, they are normally 45 locked and are only unlocked as a result of depression of amount keys and then are relocked at the end of the first half cycle of operation of the machine. The locking device is in the form of a bail suspended from the studs 12^c at the upper part of the carriage and comprising side arms 13 and cross bar 13^a having a forwardly turned flange 13^b to engage notches in the stop fingers, said flange occupying a slot in the 50 cover plate 12^a, as shown in Figs. 4 and 5. There are nine notches in each of the fingers to provide for its being locked at any one of nine different positions according to the 55 extent of movement which the associated registering lever should have. The flat

spring 13^c presses the bail forward to engage its flange with notches of the fingers and normally the flange is in engagement with the uppermost notches of all of the fingers, thus locking the latter in their lowermost positions, illustrated in Fig. 5. The side arms 13 swing freely upon the studs 12^c which are screwed into ears 12^d of the bed plate 12 of the carriage projecting rearwardly from the shaft 17. The latter has a spline groove engaged by keys of a pair of short arms 14 which carry studs 14^a engaging forward edges of the arms 13, as shown in Figs. 3, 5, and 7, for the purpose of swinging the locking bail rearward and unlocking the stop fingers whenever amount keys are depressed. This is effected by rocking the shaft 17, as will presently be described. The arms 14 must of course have a fixed lateral relation to the carriage and to this end they are formed with clips 14^c (Figs. 4 and 4^a) which embrace the ears 12^d of the carriage so as to shift laterally therewith at the same time being rotatable relative thereto.

As before stated, the amount keys operate as usual to thrust rearward the detent slide strips 214. The latter have the usual lugs 214^a which operate upon the familiar bail 402. In the present instance the cross rod 402^a of said bail is engaged by a bar 15 which, at its rear end, is jointed to an arm 16 secured to the shaft 17, so that said shaft will be rocked, by depression of any amount key, in a direction to swing the short arms 14 rearward and disengage the locking bail from the stop fingers. The bar 15 has an upper branch 15^a at its forward end shouldered to engage the bail cross rod 402^a, as shown in Fig. 3, and also has a downwardly extending branch 15^c which overlies the cross rod 902 of another familiar bail of the Burroughs machine. This latter arrangement is for the purpose of disengaging the bar from the bail cross rod 402^a and thereby permitting the locking bail to reengage and lock the stop fingers, as soon as the registering levers have moved their full extent upward in rear of their pivots.

As is usual in the Burroughs machine, the 115 bail of which the cross rod 902 forms a part is connected by a link 922 with a lever 813 in such manner that the bail is rocked forward, as to its upper portion, just at the conclusion of the first half cycle of operation of the machine. Such forward rocking is availed of in the present construction to lift the forward end of the bar 15 through a cam action between the cross rod 902 and the branch 15^c of said bar, whereby the 120 shoulder 15^b is lifted above the bail cross rod 402^a, whereupon the bar moves forward under action of a spring 15^d which connects the arm 16 to one of the keyboard cross rods 200, as shown in Fig. 3. This is accom- 125

panied by forward swinging of the finger-locking bail by its own spring 13^c. Another spring 15^e connects the bar 15 with the familiar restoring bail 613, the purpose of this spring 15^e being to reengage the shoulder 15^b with the bail cross rod 402^a when the bail 402 returns to normal.

Referring next to the matter of stepping over the stop finger carriage, this is accomplished by a push pawl 20 (Figs. 5 to 8) which operates upon a ratchet rack 21 fastened to the bed plate 12 of the carriage. Normally the pawl rests upon the inclined back of the tooth of the rack nearest the stop fingers, spaced from the shoulder just beyond so that there is lost motion when the pawl is operated, and the result is a half-step movement of the carriage for the purpose hereinbefore stated, to wit, locating the fingers 10 over the levers 611. The normal position of the carriage in which this condition exists is determined by abutment of the end of the ratchet bar against a collar 207^a secured to the shaft 207 (Fig. 5).

The pawl 20 is pivoted to the upwardly extending arm of a bell crank lever 22 and the pawl is normally retracted by a spring 22^c connecting said bell crank arm to a stud upon a frame bracket 23. The bell crank is pivoted to a lower portion of said frame bracket at 22^b and its horizontal arm is slotted to receive the rear end of a lever 24 (Fig. 7) which is pivoted upon one of the cross rods 200 under the keyboard and whose forward end is jointed to a key stem 24^a extending up through the keyboard plates and surmounted by a key top 24^b. Obviously depression of this key will rock the bell crank lever 22 and give the pawl a stroke in a direction to shift the carriage over to the right as the parts are seen in Figs. 5, 5^a and 6. A retaining pawl 25 is pivoted upon the bracket 23 just forward of the pawl 20 and pressed by a spring 25^a into engagement with the ratchet rack.

Of course it will be understood that when the machine is prepared for multiplication by depressing the key 24^b and the stop finger carriage is thus shifted a half step by the pawl 20, the retaining pawl 25 drops in behind the tooth upon the inclined back on which it and the pawl 20 were previously resting, and the retaining pawl thus holds the carriage in the shifted position. Thereafter, as the multiplication proceeds from digit to digit of the multiplier the key 24^b will of course be depressed between each series of operations and will then shift the carriage a full step each time.

When the multiplication has been completed, the product may be printed by way of the usual totaling operation. I provide for restoring the stop finger carriage to normal position as an incident to such totaling operation. To this end the familiar link 226

(Fig. 1) which is as usual connected to the total key bell crank 227, is equipped with a stud 226^a for operating upon an arm 27 which is connected by a spring 27^a to the said total key bell crank lever. Said arm is fastened to a rock shaft 200^a which, at a point farther over in the machine, has secured to it another arm 27^b (Figs. 7 and 8) having a stud 27^c. This stud extends over the cam shaped end of a lever 28 which is pivoted to an ear on the bracket 23 and extends through a slot in said bracket to engage a stud 20^d on the pawl 20. This stud extends under the retaining pawl 25 so that when the lever 28 is rocked by the camming action of the stud 27^c upon it, in a totaling operation, both pawls will be disengaged from the ratchet rack whereupon the spring 12^c will return the stop finger carriage to its normal position.

Referring next to the matter of releasing the usual rack-upholding latches 415, when operations are to be pursued which involve registering movements of levers 611 not indexed by the stop wires 270 but by the stop fingers 10, I employ a special key 40 located at the lower left hand portion of the keyboard (Fig. 18) and surmounting a stem 41 slidable through the key-board plates 212, 213, and notched like the ordinary repeat key so as to stay down indefinitely (Figs. 9 and 10). The key stem is jointed to an arm 42 secured to a rock shaft 200^b and there is a depending arm 43 also secured to this rock shaft and carrying a pivoted hook 44 engaging over the cross rod 202 of the familiar bail which the total and subtotal keys customarily retract for a similar purpose. To suit the present invention the side links 216 of the total key system are slotted for engagement with the cross rod 202 (Fig. 1) so as to provide for independent retraction of the latter. Obviously depression of the key 40 will operate through the medium of said hook 44 to retract the said cross rod and thereby disengage the latches 415 from the racks 610. This same key 40 is utilized to disable the printing mechanism and to this end there is jointed to the arm 43 a link 60 (Fig. 9) slotted in a rearward portion to embrace a guide stud 60^a on the hammer frame. This link is formed with an angular portion above said slotted portion to which a retracting spring 60^c is connected and which angular portion has a depending lip 60^b carrying a stud 60^d for effecting the disablement of the hammers 715. The latter are arranged in the usual way and adapted ordinarily to be thrown rearwardly at the close of the first half cycle of operation of the machine. This is prevented when the key 40 is down by the interposition of a comb plate 61 which is worked by the aforesaid stud 60^d.

The comb plate is pivoted between side pieces 710 of the hammer frame, as shown

in Fig. 12, and is formed with a down-turned side portion 61^a having an inclined slot occupied by the stud 60^d. Upon depression of the key 40 and rearward thrust of the link 60, the stud acts with a camming effect upon the upper side of the slot which is in rear of the pivot of the comb plate, so that the latter is thrown down from the position shown in Fig. 9 to the position shown in Fig. 10. This puts the tines of the comb plate directly in rear of portions of the rear edges of the hammers which normally extend substantially at right angles to the comb plate when so thrown down. Obviously this effectually blocks the hammers so that though released they are unable to do any printing. Normally the comb plate stands far enough away from the hammers and far enough above the aforesaid portions of the rear edges of the hammers to permit the latter full play. The said key 40 is also utilized for disabling the line spacing mechanism. The latter comprises, as usual, a pair of independently movable plates 87 and 90 mounted against the back panel of the machine and having jaws embracing the cross rod of the line spacing bail, the plate 87 being reciprocated in every operation of the machine whereas the plate 90 is reciprocated only when coupled to the plate 87 by the swinging dog 70 (Fig. 11). For the purpose of displacing this dog and thus suspending the line spacing, by depression of the key 40, the link 60 has a downward extension 60^e (Fig. 9) terminating in a laterally turned blade 60^f (Fig. 12) having a cam nose occupying a slot in the rear panel of the machine. This cam nose engages a lug 65^a on a plate 65 which is horizontally disposed on the back panel of the machine and is adapted to operate upon a stud 70^a of the aforesaid swinging dog. The said plate is permitted a limited lateral movement through slot and pin mountings and would normally be held over to the left, as the parts are seen in Fig. 11, by reason of engagement between the stud 70^a and the elongated vertical edge of the plate, 50 the dog being spring-held, as usual. The dog is mounted upon a lower portion of the plate 87 and in order to preserve the engagement between stud 70^a and the plate 65 in the reciprocation of the said plate 87, 55 the plate 65 has an elongated end portion supplying the vertical edge before mentioned.

Referring next to the matter of setting the machine in operation for repeated performances and automatically discontinuing the operations according to the multiplier digit, the present invention is chiefly characterized by the employment of a series of independently operable keys, the depression 60 of any one of which sets the machine in op-

eration and the depression of different ones of which predetermines the cessation of operation after different numbers of performances. In connection with this feature of the invention, reference may be had to Patent No. 1,033,109, issued July 23, 1912, on the invention of C. A. Lundgren. Here as there the regular electric driving equipment of the Burroughs adding machine is illustrated and the invention is shown adapted to that particular equipment.

Referring more especially to Figs. 2 and 13 to 15, the reference numeral 100 designates the series of keys which start the motor and determine the number of operations to ensue. These keys are arranged in a row, from front to rear, at the right of the keyboard (see Fig. 18) and they are numbered from 2 to 9. They are upheld by compression springs 101 arranged in cut-out portions of their stems, and they occupy slots in the upper and lower keyboard plates 213 and 212, being vertically movable in said slots and also tilttable when depressed. All of them act upon a motor-starting device in the form of a wing or shutter 102 which is pivoted between ears 103 on the lower keyboard plate 212, as illustrated most clearly in Fig. 14, and normally upheld by a spring 102^c. This shutter has a series of horizontal fingers 102^a and a wider horizontal portion 102^b at the front with a downturned blade 102^d (Fig. 13) which is adapted to act upon a stud 365 carried by one of the levers 312 of the motor-starting system. This lever and its companion lever 361 are adapted to be acted upon in the usual way by finger pressure upon the starting bar 369, but the purpose in carrying out the present invention is to start the machine without using the bar. The depression of any one of the keys 100 will start the motor (by swinging the wing or shutter 102 down) with just the same effect as finger pressure upon the bar 369. For the purpose of coöperating to this end with said wing the keys numbered from 4 to 9 are cut out in their forward edges to embrace the fingers 102^a of the wing and so provide for the shoulders at the upper ends of the cut-out portions bearing down upon said fingers and thus depressing the wing. Similarly the key numbered 3 is cut out to engage the rear portion of the wide part 102^b of the wing, and furthermore that wide part is cut out in the center, as shown in 102^e, and the key numbered 2 passes down through it and is also cut out in its forward edge to act upon this wide part of the wing with the same effect as the other keys.

The above described special keys, besides operating to start the motor, serve to bring into play certain automatic counting devices which, after operation a number of times, determined by the value of the par-

ticular key depressed, effect a release of the latter and a consequent stoppage of the machine.

A 5 detent slide strip 104 is arranged on the under side of the lower keyboard plate 212 being held thereto by screws 104^a which engage longitudinal slots in the strip, and said strip is slotted for each of the key stems, the slots 104^b normally alining with the slots of the lower keyboard plate so that the key stems, which occupy the latter slots, as before stated, stand ready to enter the slots of the detent strip, as illustrated in Fig. 13, where the parts are broken away. This 10 detent strip serves to lock down any depressed key and lock up all the other keys and, furthermore, serves to lock down the starting wing or shutter 102. A spring 104^c connecting a stud at the rear end of the strip with a stud on the keyboard plate 212, constantly exerts itself to pull the strip rearward. Normally, however, a lug 104^d at the forward part of the strip engages a forward edge of the down-turned blade 102^a of the 15 wide member 102^b of the shutter, as illustrated in Fig. 13. There is a shoulder 102^c at the upper end of this forward edge of said blade and when the shutter is depressed by any one of the keys, this shoulder passes below the lug 104^d and the detent strip thereupon springs forward taking the lug over the shoulder, as shown in Fig. 15, and locking down the shutter. Depression of a key 20 carries the lower part of its stem into a slot 25 of the detent strip and the rearward springing of the latter tilts the key sufficiently to bring a shoulder 101^a of its stem under the keyboard plate 212, as illustrated in Fig. 15, whereby the key becomes locked down. Portions 30 of the detent strip forward of its several slots move back, overlapping the respective slots of the said keyboard plate and consequently all the other keys are locked in their normal positions by reason of such 35 portions of the strip moving under them, as illustrated in Fig. 15.

Referring next to the bringing into play of counting devices by depression of any one of said special keys, the detent strip 40 serves in this connection also in that it releases an actuating pawl 106 and a holding pawl 107 for coaction with a ratchet rack 105^a formed upon a laterally extending portion of a slide plate 105. This slide plate is 45 arranged upon the upper side of the lower keyboard plate 212 and held thereto by screws 105^b which engage longitudinal slots in the plate, as clearly shown in Fig. 14, and said plate is formed to act upon the 50 several keys under differing degrees of movement in a forward direction so as to unlock the same after a number of operations of the machine have occurred corresponding with the numeral of the particular 55 key depressed. The plate is normally held

rearward by a spring 105^c which connects a stud upon it with a stud upon the keyboard plate, and when so held a series of eight interior shoulders 105^d are spaced rearwardly from the studs 101^e on the key stems 70 graded distances. Thus the rearmost of these shoulders 105^d is spaced from the stud of the 9 key, a distance representing eight steps or increments of movement of the plate under actuation by the pawl 106, the ninth step or 75 increment of movement forward of said plate serving to release the 9 key, if depressed, by reason of the action of the said shoulder against the said stud. The next rearmost shoulder of the plate, which is on the opposite side of the central opening thereof, is normally one step nearer the stud of the 8 key, and so on through the series of shoulders and keys, the same alternating on opposite sides of the key stems and the central opening of the plate for the purposes of economy of space and of extent of play of the plate. This is clearly illustrated in Fig. 14 and will be readily understood by those skilled in the art, since in general this is a 80 familiar expedient having been frequently resorted to in connection with differential limiting of movement of register actuating and type setting slide bars by different 85 amount keys.

Reverting to the matter of imparting a forward step by step movement to the controlling plate 105 and referring more particularly to Figs. 13-15 and 17^a, the detent strip 104 is formed near its rear end with two lateral extensions 104^f and 104^g, the former for normally holding the pawl 106 disengaged from the ratchet rack 105^a, and the other lateral extension serving to hold the pawl 107 normally disengaged from said ratchet rack, as illustrated in Fig. 13. This extension 104^h engages a high edge of the pawl 107 just in rear of a notch 107^a in said pawl, whereas the extension 104^g is in effect a shield over the rack teeth and against 90 which the point of the pawl 106 normally strikes. The two pawls are connected by a spring 108 which tends to engage both of them with the ratchet rack.

The pawl 107, being merely a holding or 95 detaining pawl, is pivoted to a small bracket on the under side of the keyboard plate 212 and acts as any ordinary detaining pawl to snap over the teeth of the ratchet rack as the same is advanced step by step, it being 100 understood of course that upon rearward movement of the detent strip 104 the lateral extension 104^h thereof moves off the high edge of this holding pawl and into the notch 107^a thereof so that said pawl may then freely 105 engage the ratchet rack, as illustrated in Fig. 15. Similarly the other lateral extension 104^g retreats from a position where it is obstructing the pawl 106 so that the latter 110 also moves into engagement with the rack. 115

This, being the actuating pawl, is pivoted upon the upper end of a lever 109 which is pivoted intermediate its ends on a frame stud 109^a and impelled rearwardly as to its 5 lower arm and therefore forwardly as to its upper arm by a spring 109^c. There is pivoted to the lower arm of this lever a link 110 which is slotted at its forward end to embrace a stud 622^a upon the familiar 10 rocker piece 622. The latter forms part of the usual key-releasing mechanism of a Burroughs machine (see Fig. 2), carrying the wiper pawl or cam plate 622^b for acting upon the key-releasing bail 219.

15 Normally the pawl 106 is retracted by reason of the fact that the full stroke sector 311 is holding the upper arm of the rocker piece 622 forward as usual and the stud 622^a is engaged with the forward end of 20 the slot in the link 110, spring 109^c being of course tensioned under these conditions. Upon operation of the machine the full stroke sector moves at once and the familiar spring 687 thereupon rocks the piece 622 25 carrying its upper arm rearward, and the spring 109^c vibrates the lever 109 and causes the pawl 106 to thrust the plate 105 forward one step against the tension of its spring 105^c which is inferior to the spring 109^c.

30 This is repeated with each operation of the machine until one of the shoulders 105^d operates upon the stud 101^e of the depressed key, whereupon the said key is forced forward as to its lower end and into alignment 35 with the slot of the keyboard plate 212, carrying along with it the detent strip 104 so that the wing 102 is unlocked (by disengagement of the lug 104^f from the shoulder 102^e). This of course releases the motor- 40 starting system so that the connecting clutch between the motor and the machine will be opened in the usual way at the end of the current operation. The key of course springs up to normal position as does also 45 the wing, and the detent strip 104 disengages the pawls 106 and 107 from the rack 105^a and the plate 105 springs rearward to normal, so that the machine is then ready 50 for another series of multiplication additions under control of that key or any other key of the series of keys 100, the stop finger carriage having been stepped over by depression of the key 24^b.

Inasmuch as depression of amount keys 55 for starting a series of multiplying operations, and the setting down of one of the keys 100 representing the unit digit of the multiplier, must not be accompanied by depression of the special key 40 (because the 60 latter releases all of the latches 415, and only those belonging to the numerical orders where amount keys have been depressed should be released), it becomes necessary to disable the regular key restoring 65 mechanism so as to prevent the relatching

of the racks of those orders and consequent interference with repeated registering of the multiplicand for the initial partial product. This disablement is accomplished by curtailing the vibration of the aforesaid 70 familiar rocker piece 622. To this end the detent slide stop 104 is provided with an additional pendant lug 104^f (Figs. 13 and 15) which is adapted to serve the function in question in co-operation with a lever 112. 75 The short arm of the latter, forward of its pivot 112^a, has a raised edge which normally engages said lug, as shown in Fig. 13, whereby this arm of the lever is depressed and its long rear arm held up. This long 80 arm at its rear extremity takes the form of a hook 112^b which, when lowered, presents itself in the path of movement of the stud 622^a in order to prevent the spring 687 from rocking said piece to the full extent. When 85 the detent strip 104 springs rearward as a result of depression of one of the keys 100, the lug 104^f moves forward of the raised edge of the short forward arm of the lever 112 and the greater weight of the long arm 90 of said lever lowers it into position for limiting the movement of the rocker piece 622. This limitation of the latter's movement prevents the wiper pawl 622^b from passing the roller 219^a of the key-releasing bail and 95 consequently the bail will not partake of any key-releasing movement.

The setting up of a multiplicand by depression of amount keys and the conditioning of the multiplying equipment by depressing the key 24^b and then depressing one of the multiplier keys 100, without depression of the key 40 or use of a simple non-print key such as sometimes employed 100 in this class of machines, would of course 105 result in the printing of the multiplicand in each of the initial series of operations for registering the partial product. This would generally be a useless procedure and one that therefore might just as well be dispensed with as the successive printing of 110 the multiplicand is dispensed with in subsequent series of operations when the key 40 is depressed. On the other hand it is desirable to print the multiplicand once at 115 the beginning of the series of multiplying operations. To do this and avoid further printing of the multiplicand during the first series of operations, the first operation can be performed without depression of 120 the multiplier key but by either pulling the handle of the machine or operating the starting bar 369. Then the key 40 would be depressed, disabling all of the printing hammers and disabling the line spacing mechanism, and also disabling all of the latches 415. Then that one of the multiplier keys bearing the numeral one number less than the digit of the multiplier would be depressed and the machine would perform the 125 130

proper number of operations which, added to the initial operation, would make the correct number of registrations of the multiplicand to accord with the digit of the 5 multiplier. It will be understood of course that when proceeding in this manner the amount keys would be released in the initial operation in the ordinary way, but corresponding stop fingers 10 would be set in the 10 operation so that in subsequent operations the actuating levers would be properly controlled.

In order to reduce the amount of manipulation in starting a series of multiplying 15 operations I have devised, as a further elaboration of my present invention, a modified construction which is illustrated in Figs. 19 to 22. This provides for depression of the key 40 at the outset but delayed effectiveness thereof, so that the same result will 20 ensue as just above explained, to wit, the printing of the multiplicand in the first operation but not in the rest of the operations of the first series. Referring to said Figs. 25 19 to 22, the depending arm 43 of the bell crank, which the key 40 operates, is not directly pivoted to the bar 60 as before, but is connected by spring A to a forward extension of said bar, and the latter is formed 30 with a wide slot *a* into which projects the stud of the arm 43 to which the spring is attached. Upon depression of the key the bar 60 is not moved but the spring A is stretched (Fig. 20) and at the close of the 35 operation of the machine moves the bar rearward (Fig. 22) so that in the ensuing operations it will release the rack latches 415 and disable the printing hammers and the line spacing mechanism. The bar is 40 normally held forward by a stud *b* on the framework of the machine (Figs. 19 and 20). This stud engages an elongated notch in the under edge of the bar 60 but the width of the slot *a* is such as to provide for 45 an upward swinging of the bar sufficient to disengage it from said stud (Fig. 21). The stud 43^a, which occupies the slot *a* of the bar 60, couples the arm 43 to another bar B which extends alongside the bar 60 and 50 has a lug B' underlying the same. There is a wiper pawl C pivoted to this bar B at *c* and formed with a lug C' which overlies the upper edge of the bar 60, being normally held in engagement therewith by a spring 55 *c'* (Fig. 19).

When the key 40 is depressed the bar B is moved rearward so that the rear edge of the lower part of its pawl C comes against a stud 613^b upon the restoring frame 613 60 and is tilted thereby as shown in Fig. 20. When the frame lowers in the first part of the operation of the machine, said stud is carried below the pawl and the latter is swung into line with the stud by its spring 65 *c'*. Consequently when the restoring frame

returns to normal at the conclusion of the operation of the machine (Fig. 21) the stud acts against the under edge of the pawl and thereby lifts the bar B and with it the bar 60 so that the latter is disengaged from the frame stud *b* and immediately moves rearward under the action of the spring A which is superior to the spring 60^a. Of course, when the key 40 is released, the action of the spring A is nullified and the 75 spring 60^a returns the bar C to normal together with the key and its connections. A forward extension of the bar 60 takes the form of a hook 60^d engaging over the bail cross-rod 202 to retract the same and the 80 rack latches as does the hook 44 of the before-described construction.

In order that the user of the machine may readily determine the stage reached in the multiplying operations, I preferably provide an index to show the numerical order of the multiplier digit or, in other words, the lateral position of the stop carriage. To this end the casing of the machine is provided with a transverse slot 30 just 85 above the keyboard, as illustrated in Fig. 18, and alongside this slot is mounted an index plate 31 graduated and inscribed according to the capacity of the machine. In the present instance the machine is a so-called 15- 90 bank machine, that is there are fifteen rows of amount keys. Consequently the index plate is marked from zero to 15. A pointer 32 is fastened to the stop pin carriage and projects up through the slot 30 and over 100 the plate 31, as clearly illustrated in Fig. 1 and also in Fig. 18. It will be obvious that this index finger will travel along with the carriage and register with one after the other of the graduations on the index plate 105 31. The zero or normal graduation mark on the plate is a half space from the graduation associated with the numeral 1 to accord with the half step movement of the carriage, as before explained, which puts the 110 stop fingers in line with the registering lever 611 respectively. Of course the other graduations are spaced apart to correspond with the full step movements of the carriage and as the latter is shifted between series of 115 multiplying operations or to take up orders where ciphers occur in the multiplier or index fingers 32, will move from registry with one numbered graduation to the next.

In addition to the special keys already 120 described and the total and subtotal keys, there are the usual "elimination", "correction" and "repeat" keys which appear in plan in Fig. 18, initialed accordingly, and which function in the usual manner through 125 familiar connections which require no special description as they are not directly concerned with an embodiment of the present invention.

While the constructions hereinbefore point- 130

ed out for embodying said invention are well adapted to the fulfilment of the objects primarily stated, it is nevertheless to be understood that the invention is not necessarily limited to this particular form of embodiment but the same is susceptible of considerable modification and the invention may be carried out in a variety of ways.

I claim:

10 1. In a machine of the character described, the combination of an accumulator; actuators for the respective members thereof; keys for releasing and limiting movement of said actuators; normally-locked 15 stops adapted when unlocked to be set by released actuators; means for unlocking said stops as an incident to release of the actuators and relocking them when set by released actuators; and a laterally-shiftable 20 support for the stops.

2. In a machine of the character described, the combination of an accumulator; reciprocating actuators for the respective members thereof; keys for releasing and determining the extent of reciprocating movement of said actuators; stops settable in line with the latter respectively and normally locked against movement thereby; means for unlocking the stops by the keys with 30 provisions for relocking them after one or more have been moved by the actuators; and a laterally shiftable support for the stops.

3. In a machine of the character described, the combination of an accumulator; actuators for the respective members thereof; keys for releasing and limiting movement of said actuators; stops set by released actuators; means for locking and unlocking said stops; a laterally shiftable support for the latter; means for zeroizing the accumulator; and means operated thereby for restoring the said support to normal.

4. In a machine of the character described, the combination of an accumulator; actuators for the respective members thereof; keys for releasing and limiting movement of said actuators; stops set by released actuators; means for locking and unlocking said stops; a laterally shiftable support for the latter; and manipulative means for releasing the actuators independently of the keys to provide for measuring movements of actuators by the locked stops.

5. In a machine of the character described, the combination of an accumulator; actuators for the respective members thereof; keys for releasing and limiting movement of said actuators; stops set by released actuators; means for locking and unlocking said stops; a laterally shiftable support for the latter; manipulative means for releasing the actuators independently of the keys to provide for measuring movements of actuators by the locked stops; printing mecha-

nism; and means for disabling the same by said manipulative means.

6. In a machine of the character described, the combination of an accumulator; actuators for the respective members thereof; keys for releasing and limiting movement of said actuators; stops set by released actuators; means for locking and unlocking said stops; a laterally shiftable support for the latter; manipulative means for releasing the actuators independently of the keys to provide for measuring movements of actuators by the locked stops; printing and line spacing mechanisms; and means for disabling the same by said manipulative means.

7. In a machine of the character described, the combination of an accumulator; actuators for the respective members thereof; keys for releasing and limiting movement of said actuators; stops set by released actuators; means for locking and unlocking said stops; a laterally shiftable support for the latter; manipulative means for releasing the actuators independently of the keys to provide for measuring movements of actuators by the locked stops; and means for delaying the effectiveness of said means until after initial advance of the actuators for registration of a multiplicand.

8. In a machine of the character described, the combination of an accumulator; actuators for the respective members thereof; keys for releasing and limiting movement of said actuators; stops set by released actuators; means for locking and unlocking said stops; a laterally shiftable support for the latter; manipulative means for releasing the actuators independently of the keys to provide for measuring movements of actuators by the locked stops; printing mechanism; means for disabling the same by said manipulative means; and means for delaying effectiveness of said latter means until after printing of a multiplicand.

9. In a machine of the character described, the combination with an accumulator, actuating levers therefor, keys and connections for releasing the levers and limiting movement thereof, and operating mechanism; of a laterally shiftable carriage containing slidable pins and normally positioned with said pins out of alignment with the levers; a key and connections for shifting the carriage step by step to first align its stop pins with the levers, and then shift them from order to order; locking devices on the carriage normally locking the stop pins against movement by the levers; means for disabling said locking devices by operation of amount keys; means for reenabling them by the operating mechanism at an intermediate stage in the

operation thereof; and manipulative means for releasing the levers independently of amount keys for the purpose described.

10. In a machine of the character described, the combination with an accumulator, actuating levers therefor, keys and connections for releasing the levers and limiting movement thereof, and operating mechanism; of a laterally shiftable carriage containing slidable pins and normally positioned with said pins out of alinement with the levers; a ratchet rack on the carriage; a pawl engaging the rack; a key and connections for vibrating the pawl; locking devices on the carriage normally locking the stop pins against movement by the levers; means for disabling said locking devices by operation of amount keys; means for reenabling them by the operating mechanism at an intermediate stage in the operation thereof; and manipulative means for releasing the levers independently of amount keys for the purpose described.

11. In a machine of the character described, the combination with an accumulator, actuating levers therefor, keys and connections for releasing the levers and limiting movement thereof, and operating mechanism; of a laterally shiftable carriage containing slidable pins and normally positioned with said pins out of alinement with the levers, each pin having a series of notches; a key and connections for shifting the carriage step by step to first aline its stop pins with the levers, and then shift them from order to order; a locking bail on the carriage normally engaging notches of the stop pins; connections for disengaging said bail through operation of amount keys; means for effecting reengagement of the bail by the operating mechanism at an intermediate stage in the operation thereof; and manipulative means for releasing the levers independently of amount keys for the purpose described.

12. In a machine of the character described, the combination with an accumulator, actuating levers therefor, keys and connections for releasing the levers and limiting movement thereof, and operating mechanism including a vibrating bail; of a laterally shiftable carriage containing slidable pins and normally positioned with said pins out of alinement with the levers, each pin having a series of notches; a key and connections for shifting the carriage step by step to first aline its stop pins with the levers, and then shift them from order to order; a locking bail on the carriage normally engaging notches of said stop pins; a thrust bar connected to said bail and separably engaging a cross-rod of the amount key connections and formed for engagement with the vibrating bail of the operating mechanism; and manipulative means for

releasing the levers independently of amount keys for the purpose described.

13. In a machine of the character described, the combination with an accumulator, actuating levers therefor, keys and connections for releasing the levers and limiting movement thereof, totaling devices, and operating mechanism; of a laterally shiftable carriage containing slidable pins and normally positioned with said pins out of alinement with the levers; a ratchet rack on the carriage; a pawl engaging the rack; a key and connections for vibrating the pawl; locking devices on the carriage normally locking the stop pins against movement by the levers; means for disabling said locking devices by operation of amount keys; means for reenabling them by the operating mechanism at an intermediate stage in the operation thereof; manipulative means for releasing the levers independently of amount keys for the purpose described; a spring for returning the carriage to normal; a retaining pawl; and connections with the totaling devices for disengaging said retaining pawl and the actuating pawl from the rack.

14. In a machine of the character described, the combination with an accumulator, actuating levers therefor, latches for said levers, keys and connections for individually retracting the latches and for limiting movement of levers, and operating mechanism; of a laterally shiftable carriage containing slidable pins and normally positioned with said pins out of alinement with the levers; a key and connections for shifting the carriage step by step to first aline its stop pins with the levers, and then shift them from order to order; locking devices on the carriage normally locking the stop pins against movement by the levers; means for disabling said locking devices by operation of amount keys; means for reenabling them by the operating mechanism at an intermediate stage in the operation thereof; and a key and connections for collectively retracting the latches.

15. In a machine of the character described, the combination with an accumulator, actuating levers therefor, latches for said levers, keys and connections for individually retracting the latches and for limiting movement of levers, and operating mechanism; of a laterally shiftable carriage containing slidable pins and normally positioned with said pins out of alinement with the levers; a key and connections for shifting the carriage step by step to first aline its stop pins with the levers, and then shift them from order to order; locking devices on the carriage normally locking the stop pins against movement by the levers; means for disabling said locking devices by operation of amount keys; means for reenabling them by the operating mechanism

- at an intermediate stage in the operation thereof; a cross rod for collectively retracting the latches; a key and spring connections between it and the cross rod; means 5 normally obstructing retraction of the latter while permitting depression of said key and tensioning of the spring; and means actuated by the operating mechanism at the close of a cycle of operations thereof to liberate the cross rod.
16. In a machine of the character described, the combination with an accumulator, actuating levers therefor, latches for said levers, keys and connections for individually retracting the latches and for limiting movement of levers, printing hammers, and operating mechanism; of a laterally shiftable carriage containing slidable pins and normally positioned with said pins out 10 of alinement with the levers; a key and connections for shifting the carriage step by step to first aline its stop pins with the levers, and then shift them from order to order; locking devices on the carriage normally locking the stop pins against movement by the levers; means for disabling said locking devices by operation of amount keys; means for reenabling them by the operating mechanism at an intermediate stage 15 in the operation thereof; and a key and connections for collectively retracting the latches and disabling the printing hammers.
17. In a machine of the character described, the combination with an accumulator, actuating levers therefor, latches for said levers, keys and connections for individually retracting the latches and for limiting movement of levers, printing hammers, and operating mechanism; of a laterally shiftable carriage containing slidable pins and normally positioned with said pins out 20 of alinement with the levers; a key and connections for shifting the carriage step by step to first aline its stop pins with the levers, and then shift them from order to order; locking devices on the carriage normally locking the stop pins against movement by the levers; means for disabling said locking devices by operation of amount keys; means for reenabling them by the operating mechanism at an intermediate stage 25 in the operation thereof; and a key; a plate movable into position for obstructing the printing hammers; a thrust bar operatively connected to said plate; a spring connecting 30 said bar and said key; means normally obstructing the bar while permitting depression of the key and tensioning of the spring; connections between the bar and latches for collectively retracting the same; and means actuated by the operating mechanism at the close of a cycle of operation thereof to liberate the latch retracting connections and the thrust bar.
18. In a machine of the character described, the combination with an accumulator, actuating levers therefor, latches for said levers, keys and connections for individually retracting the latches and for limiting movement of levers, printing hammers, and operating mechanism; of a laterally shiftable carriage containing slidable pins 35 and normally positioned with said pins out of alinement with the levers; a key and connections for shifting the carriage step by step to first aline its stop pins with the levers, and then shift them from order to order; locking devices on the carriage normally locking the stop pins against movement by the levers; means for disabling said locking devices by operation of amount keys; means for reenabling them by the operating mechanism at an intermediate stage 40 in the operation thereof; and a key; a plate movable into position for obstructing the printing hammers; a thrust bar operatively connected to said plate; a spring connecting 45 said bar and said key; means normally obstructing the bar while permitting depression of the key and tensioning of the spring; connections between the bar and latches for collectively retracting the same; and means actuated by the operating mechanism at the close of a cycle of operation thereof to liberate the latch retracting connections and the thrust bar.
19. In a machine of the character described, the combination with an accumulator, actuating levers therefor, latches for said levers, keys and connections for individually retracting the latches and for limiting movement of levers, printing hammers, and operating mechanism; of a laterally shiftable carriage containing slidable pins 50 and normally positioned with said pins out of alinement with the levers; a key and connections for shifting the carriage step by step to first aline its stop pins with the levers, and then shift them from order to order; locking devices on the carriage normally locking the stop pins against movement by the levers; means for disabling said locking devices by operation of amount keys; means for reenabling them by the operating mechanism at an intermediate stage 55 in the operation thereof; and a key; a plate movable into position for obstructing the printing hammers; a thrust bar operatively connected to said plate; a spring connecting said bar and said key; means normally obstructing the bar while permitting depression of the key and tensioning of the spring; connections between the bar and latches for collectively retracting the same; and means actuated by the operating mechanism at the close of a cycle of operation thereof to liberate the latch retracting connections and the thrust bar.
20. In a machine of the character described, the combination with an accumulator, actuating levers therefor, latches for said levers, keys and connections for individually retracting the latches and for limiting movement of levers, printing hammers, and operating mechanism; of a laterally shiftable carriage containing slidable pins 60 and normally positioned with said pins out of alinement with the levers; a key and connections for shifting the carriage step by step to first aline its stop pins with the levers, and then shift them from order to order; locking devices 65 and normally positioned with said pins out of alinement with the levers; a key and connections for shifting the carriage step by step to first aline its stop pins with the levers, and then shift them from order to order; locking devices

on the carriage normally locking the stop pins against movement by the levers; means for disabling said locking devices by operation of amount keys; means for reenabling them by the operating mechanism at an intermediate stage in the operation thereof; a key and connections for collectively retracting the latches; a thrust bar operated by said key; and a member operated by the thrust-bar and operating upon the line-spacing coupler substantially as and for the purpose described.

21. In a machine of the character described, the combination with a prime mover, differential accounting elements, manipulative amount determining devices, detent means, and detent-releasing means; of a set of special keys, a detent member controlled thereby, means for disabling the aforesaid detent-releasing means by said last mentioned detent member, a restoring device for the latter, and means for actuating said restoring device step by step in successive operations of the prime mover.

22. In a machine of the character described, the combination with a prime mover, differential accounting elements, manipulative amount determining devices, detent means, and detent-releasing means; of a set of special keys, a detent member controlled thereby, means for disabling the aforesaid detent-releasing means by said last mentioned detent member, a restoring device for the latter, and means for actuating said restoring device step by step in successive operations of the prime mover, said latter means being normally disabled by said detent member.

23. In a machine of the character described, the combination with a prime mover, differential accounting elements, manipulative amount determining devices, detent means, and detent-releasing means; of a set of independently depressible and tiltable special keys, a detent strip slotted to receive the latter and spring-actuated, means normally restraining the strip and adapted to be displaced by the keys, means for disabling the aforesaid detent-releasing means by said strip, a controller plate constructed for differential action upon the keys to restore them, and means for actuating said plate step by step in successive operations of the prime mover.

24. In a machine of the character described, the combination with a prime mover, differential accounting elements, manipulative amount determining devices, detent means, and detent-releasing means; of a set of independently depressible and tiltable special keys, a detent strip slotted to receive the latter and spring-actuated, means normally restraining the strip and adapted to be displaced by the keys, means for disabling the aforesaid detent-releasing means

by said strip, a controller plate constructed for differential action upon the keys to restore them and having a ratchet rack, and a pawl arranged to operate thereon under actuation by the prime mover.

25. In a machine of the character described, the combination with a prime mover, differential accounting elements, manipulative amount determining devices, detent means, and detent-releasing means; of a set of independently depressible and tiltable special keys, a detent strip slotted to receive the latter and spring-actuated, means normally restraining the strip and adapted to be displaced by the keys, means for disabling the aforesaid detent-releasing means by said strip, a controller plate constructed for differential action upon the keys to restore them and having a ratchet rack, and a pawl arranged to operate thereon under actuation by the prime mover, the said detent strip normally preventing engagement between the pawl and the rack.

26. In a machine of the character described, the combination with a prime mover, differential accounting elements, manipulative amount determining devices, detent means, and detent-releasing means; of a set of independently depressible and tiltable special keys, a detent strip slotted to receive the latter and spring-actuated, means normally restraining the strip and adapted to be displaced by the keys, means for disabling the aforesaid detent-releasing means by said strip, a controller plate constructed for differential action upon the keys to restore them and having a rack and being spring-held, a pawl arranged to operate upon said rack under actuation by the prime mover, and a detaining pawl arranged to engage said rack.

27. In a machine of the character described, the combination with a prime mover, differential accounting elements, manipulative amount determining devices, detent means, and detent-releasing means; of a set of independently depressible and tiltable special keys, a detent strip slotted to receive the latter and spring-actuated, means normally restraining the strip and adapted to be displaced by the keys, means for disabling the aforesaid detent-releasing means by said strip, a controller plate constructed for differential action upon the keys to restore them and having a rack and being spring-held, a pawl arranged to operate upon said rack under actuation by the prime mover, and a detaining pawl arranged to engage said rack, said two pawls being normally prevented by said detent strip from engaging the rack.

28. In a machine of the character described, the combination with a motor-driven prime-mover, and starting devices; of a movable member for operating the latter, a

set of independently operable keys for moving said member, a detent device for detaining the same, and means operated step-by-step by the prime mover and adapted to 5 restore the detent device.

29. In a machine of the character described, the combination with a motor-driven prime-mover, and starting devices; of a movable member for operating the latter, a set of independently operable keys for moving said member, a detent device for detaining the same and locking the operated key, and means actuated step-by-step by the prime mover and adapted to unlock the 10 operated key and restore the detent device.

30. In a machine of the character described, the combination with a motor-driven prime-mover, and starting devices; of a set of independently compressible and 15 tilttable special keys; a pivoted wing engaged by said keys and adapted to operate said starting devices; a spring-actuated detent strip slotted to receive said keys, normally restrained by said wing, and adapted 20 to engage said wing to hold it down when depressed by any one of said keys, the strip then tilting the key to lock the same down; means for disabling the aforesaid detent-releasing means by said strip; a controller plate constructed for differential action 25 upon the keys to restore them; and means for actuating said plate step-by-step in successive operations of the prime mover.

31. In a machine of the character described, the combination with a prime mover, differential accounting elements, manipulative amount determining devices, detent means, detent-releasing means, a power drive applied to the prime mover, and starting devices; of a movable member for operating the latter; a set of independently operable keys for moving said member; a detent member controlled by said keys; means for disabling the aforesaid detent-releasing means by said last mentioned detent member; a restoring device for the latter; and means for actuating said restoring device step-by-step in successive operations of the prime mover.

32. In a machine of the character described, the combination with a prime mover, differential accounting elements, manipulative amount determining devices, detent means, detent-releasing means, a power drive applied to the prime mover, and starting devices; of a movable member for operating the latter; a set of independently operable keys for moving said member; a detent member for detaining the same; means for disabling the aforesaid detent-releasing means by said last mentioned detent member; a restoring device for the latter; and means for actuating said restoring 60

device step-by-step in successive operations of the prime mover.

33. In a machine of the character described, the combination with a prime mover, 65 differential accounting elements, manipulative amount determining devices, detent means, detent-releasing means, a power drive applied to the prime mover, and starting devices; of a set of independently de- 70 pressible and tilttable special keys; a pivoted wing engaged by said keys and adapted to operate said starting devices; a spring-actuated detent strip slotted to receive said keys, normally restrained by said wing, and adapted 75 to engage said wing to hold it down when depressed by any one of said keys, the strip then tilting the key to lock the same down; means for disabling the aforesaid detent-releasing means by said strip; a controller plate constructed for differential action 80 upon the keys to restore them; and means for actuating said plate step-by-step in successive operations of the prime mover.

34. In a machine of the character described, the combination with an accumulator, actuating levers therefor, latches for said levers, keys and connections for individually retracting the latches and for limiting movement of levers, printing hammers, 85 and operating mechanism including a reciprocating member having a stud; of a laterally shiftable carriage containing slide- 90 able pins and normally positioned with said pins out of alignment with the levers; a key 95 and connections for shifting the carriage step by step to first align its stop pins with the levers, and then shift them from order to order; locking devices on the carriage normally locking the stop pins against 100 movement by the levers; means for disabling said locking devices by operation of amount keys; means for reenabling them by the operating mechanism at an intermediate stage in the operation thereof; a 105 key; a plate movable into position for obstructing the printing hammers; a thrust bar operatively connected to said plate; a spring connecting said bar and said key; a fixed stud normally obstructing the bar; a 110 supplemental bar connected to the key and having a one-way engagement with the said thrust bar for freeing the same from said fixed stud; and a wiper pawl on said supplemental bar coacting with the stud on the 115 aforesaid reciprocating member of the operating mechanism; substantially as described.
